VAPOR DISCHARGE DEVICE

Filed March 2, 1926

UNITED STATES PATENT OFFICE

TED E. FOULKE, OF NUTLEY, NEW JERSEY, ASSIGNOR TO GENERAL ELECTRIC VAPOR LAMP COMPANY, OF HOBOKEN, NEW JERSEY, A CORPORATION OF NEW JERSEY

VAPOR DISCHARGE DEVICE

Application filed March 2, 1926. Serial No. 91,723.

The present invention relates to vapor discharge lamps of the electrode type. The invention relates more particularly to electrodes for such devices and the forms of such electrodes, to the in-leads for the electrodes, to method and means for protecting the seals for the leads, to the particular atmospheres provided in the devices, and to other relations of various parts to one another.

10 The invention further relates to vapor discharge devices which have a complementary gas or vapor therein to aid in the transfer of electrical energy from a source to a radiation sustaining or emitting gas or vapor.

15 Various objects and advantages of the invention will be apparent from the specification and claims from the accompanying drawings.

In vapor discharge devices such as positive column, negative glow, and vapor arc lamps, vapor or gaseous rectifiers, in electronic valve devices and the like radiations are produced or sustained in a gas or vapor by energy applied thereto through electrodes terminating therein or by induction. In devices of this kind in which electrodes are used for applying the energy sputtering of the electrodes is caused by bombardment of the material thereof principally by positive ions of the gas or vapor of the devices. I have found however that the rate of sputtering is directly proportional both to the atomic weight of the gas or vapor and to the atomic weight of the metal or material of the electrode. Further to reduce the amount of sputtering to a minimum I make the electrodes of metal or material of low atomic weight and use a gas or vapor of low atomic weight for sustaining the discharge.

40 Again I find that the best gases for sustaining radiation discharges and particularly radiations of desired colors are not always the most efficient in the transformation of the applied electrical energy to radiations.

45 And in most cases the gases and vapors most suitable for sustaining radiations or desired radiations are not those having the lowest atomic weights and therefore not the most desirable from the point of view of preventing electrode sputtering. But I do find that

certain gases which are most suitable for the efficient transformation of the energy are also of very low atomic weights and therefore most desirable from the standpoint of a small degree of electrode sputtering when 55 used in devices of this kind. Also those gases most desirable on account of the color or quantity of radiations therefrom are not those having the lowest atomic weights.

But I find that certain gases which are desirable on account of the kind and nature of radiations sustainable thereby may be used in very dilute or small quantities together with other gases which either do not produce radiations when these first said gases are 60 used or produce light or radiations which are completely or substantially completely masked by the desired radiations of first said gases and that the gases can be chosen and mixtures thereof used so that one gas is 65 highly efficient as an energy transmitter and another is highly efficient as an illuminant. In such a mixture the transmitter serves to pass energy from the source to the illumination or radiation supporting gas. In such an 70 action the atoms or molecules of the energy transmitting gas pass energy on to atoms or molecules of the radiation producing gas during collisions therewith. Such collisions 75 are known in physics as collisions of the second order.

Accordingly in devices of this kind I use a mixture of certain gases comprising two components, one a radiation supporting component and a component for transferring energy from the source to the radiation supporting component. For the radiation supporting component I use a desired gas or vapor in comparatively small quantities and 80 use the energy transforming component in large quantities.

Further I find that the energy transferring component can be chosen as a gas or vapor having a very low atomic weight, 85 helium having a very low atomic weight and being very efficient in transferring energy to another gas or vapor. For the radiation supporting medium a gas is chosen with as low an atomic weight as possible, neon being suit- 90 100

able both in respect to the desirability of the color of its radiation and its atomic weight. Further, I find that by using a mixture containing usually over 95% of helium and usually not more than 5% of neon that illumination can be very efficiently produced in a negative glow lamp.

Argon is used with the helium in some cases to assist in energy transmission as its low ionizing potential is of material assistance in starting the device into operation, but usually in quantities not over 5% on account of its comparatively high atomic weight. Hydrogen is in some cases used in small quantities to keep the surfaces of the electrodes clean.

In the specification and the drawings there is shown and described the application of my invention to and the embodiment thereof in lamps of the negative glow type but it is to be understood that various parts thereof are also applicable to other lamps such as vapor arc lamps and positive column lamps, and to other electrical devices.

In negative glow lamps non-uniformity of electrode material, of temperature at different points on the discharge surface of the electrode, and of other conditions and characteristics produce or cause dark spots on the electrode or areas at which no glow discharge is produced. To preclude the occurrence of such dark spots and to overcome the effect of them I provide an electrode having a multiplicity of comparatively closely spaced points or projections or extended ridges which act as discharge points and as points of high current density whereby there is insured the production of radiation at a multiplicity of points uniformly distributed over a discharge area. In cases and under conditions where some areas would be dark this uniform distribution of light through the multiplicity of points will overcome the effect of the dark spots. In other cases discharges will be started up in the dark spots by the production of radiation at points within the dark areas. In any case a uniform and desirable lighting effect will be produced.

In discharge devices of the sealed-in electrode type difficulty is experienced and the life of the device is impaired by deterioration of the seal from the action of positive ions and electrons which are produced by the discharge and which upon contact therewith attack and break up the materials of the seal. To overcome the action of the positive ions and also of the electrons I provide at the seal a coating of material which will prevent the positive ions and electrons from reaching the materials of the seal.

In discharge devices of the sealed-in electrode type difficulty is experienced due to the disintegration of the glass at the seal-in through bombardment thereof by positive ions from the electrodes and from the elec-

trode leads. This bombardment is particularly destructive when the seal-ins of both electrodes are close together or at a common seal due to the strong electrostatic field between the leads and between the electrodes and to the consequent high energy values which the positive ions possess when they strike the material of the seal-ins.

The glass of the seal-in is disintegrated by the positive ions when they strike it and the metal of the glass upon being freed is sputtered throughout the lamp and onto the wall thereof where it causes blackening. This sputtering takes place at such a high rate that the lamp is quickly reduced to such a low rate of efficiency as to be unsuitable for use. In the case of lead glass this rate of depreciation is particularly high on account of the high atomic weight of the metal lead, the rate of sputtering being proportional, I have discovered, to the atomic weight. I have further discovered that metals of low atomic weight and particularly those having in addition high boiling points are sputtered at a very low rate and that such metals or compounds thereof serve as highly efficient protecting means for the seal-ins and for the leads thereat and that the length of life of the device in which they are used may be increased by 100% and more by the use of such protective materials.

Materials which I have found preferable for such protecting means are sleeves of lithium, aluminum, magnesium, and other light weight metals, and coatings of compounds of light metals such as caesium oxide, lithium oxide, magnesium oxide, calcium oxide, aluminum oxide or carbonates of these metals, and so on. These metals, aluminum, lithium, magnesium, calcium and so on are also applicable as paints to the surfaces to be protected. Lithium and lithium oxide I find are very highly desirable for this use on account of the low atomic weight and the high boiling point of the metal. The lithium oxide is applied, for example, by making a paste thereof with distilled water, forming a coating on the parts to be protected and drying the water therefrom.

The electrode material itself is of course subject to the sputtering action in a manner similar to that of the material of the seal-ins and of the leads, and these also may have the amount or rate of sputtering therefrom decreased by forming a coating thereon of metal of low atomic weight or of a compound thereof, or the electrode itself is made of a low atomic weight metal or alloy. This coating may be applied by electro-plating, dipping, painting or any other well known means.

I find, however, that this coating may be derived from a material used as a protective coating at the seal-ins, the coating of protective material being sputtered thereonto by bombardment of the protective coating on the

seal-ins by positive ions during preliminary or initial use of the lamp or device. The coating may also be applied by heating the oxide in a partial vacuum. I find it imperative, however, to provide the seal-ins with the protective coating prior to any use of the lamp or device because of the comparatively heavy atomic weight of the metal of the glass and the attendant rapid deterioration thereof and blackening of the lamp when the protective coating is absent from the seal-ins, the rate of blackening being so rapid that the device is rendered unsuitable for use before a protective coating can be formed at the seal-ins before such a degree of deterioration occurs.

In negative glow lamps it is usually found necessary to employ resistances in series with a lamp for stabilizing a current flow in order that advantageous pressures of gases may be employed in accordance with laws well known in the art. In one form of device embodying this invention a part of the glass of the envelope is used as the stabilizing resistance, the lead to an electrode being terminated at a short distance from the electrode and glass being fused thereover to serve as a resistor between the end of the lead and the electrode terminal.

In the accompanying drawings is shown for purposes of illustration one form of mechanism with certain modifications thereof embodying the invention, in which

Fig. 1 is an elevation view of a glow lamp having circular electrodes in which are turned grooves and ridges to produce a multiplicity of points extended uniformly over the discharge areas of the electrodes.

Fig. 2 is a face elevation view of a flat electrode which is scored at a multiplicity of lines to produce points extended uniformly over the discharge area of the electrode.

Fig. 3 is an elevation view of a flat electrode showing a face scored to provide projecting points,

Fig. 4 is an elevation view of a lamp similar to that of Fig. 1 but with flat scored electrodes such as is shown in Fig. 3,

Fig. 5 is a vertical elevation view in part section of an electrode seal-in part of a lamp or the like showing electrodes formed over the glass of the seal-in and with protective material on the seal-in between the electrodes, and

Fig. 6 is a vertical section view in elevation of a glass seal-in stem with an electrode lead having an end sealed into said stem and terminating therein, an electrode in the form of a cap mounted on said stem and protective material below the electrode.

Referring to Figs. 1 and 2 of the drawings the envelope 1 having a screw base 2 has mounted therein the electrodes 3 connecting with said base 2 by the leads 4 in the conventional manner. On said electrodes 3 which are circular in cross section are formed

the spiral ridges 6 which present a plurality of projecting points extending uniformly over the discharge area of the electrodes. At the points of seal-in of said leads 4 through their supporting stems 7 and over the leads 70 and stems 6 at and near these points is provided a covering of protective material 8 of lithium oxide, calcium oxide, magnesium oxide, aluminum oxide, or sleeves or paint of metal of these compounds or the like. 75

Referring to Figs. 3 and 4 the glow electrodes 3', 3' are in the form of flat sheets mounted parallel to each other on the leads 4, 4 and are formed with scorings therein or grooves to provide the raised points 6'. The leads 4, 4 and the seal-in stems 7, 7 have coatings of protective material 8, 8 thereon and on leads 4, 4, between the coatings 8 and the electrodes 3' is mounted the baffle plate 10 which is formed of lithium oxide, calcium 85 oxide, aluminum oxide or the like or of material such as mica, for example, having a coating of protective material thereon.

In Fig. 5 the stem 14 carries the seal-in stems 15, 15 through which are sealed the 90 electrode leads 16, 16 which terminate at a short distance above the upper end of the respective stems 15, 15. Mounted about stems 15, 15 and making electrical contact at the upper ends of said lead-ins 16, 16 are the electrodes 18, 18 which are in the form of caps. Below said electrodes 18 on stems 15 and on stem 14 is the covering of protective material 20.

In Fig. 6 the stem 21 has sealed thereinto 100 and terminating therein the electrode lead 22. About the upper end of stem 21 is mounted the electrode 24 which is in the form of a cap fitted closely to the stem. The glass of the stem about the end of lead 22 serves as a 105 stabilizing or ballasting resistance for the circuit to which said electrode 24 may be connected, a glass suitable in this use is one containing an appreciable amount of lead or aluminum, such for example as a lead or an aluminum borosilicate glass. Below said electrode 24 and for an appreciable distance there is provided the covering 25 of the protective material above described. 110

It is to be understood that the practice and application of my invention is not limited to the use of the metals above described and the compounds thereof because as will be apparent varying degrees of efficiency over the non-protected devices can be obtained by selecting the protecting materials which are less responsive to the sputtering effect of the positive ions than is the material to be protected. 115

I have made negative glow lamps having 125 a filling of helium about 95% and neon about 5% and having magnesium electrodes and with a metal oxide of low atomic weight as a protective covering between the electrodes which will start and operate at voltages as 130

low as 70 volts direct current, and 50 volts alternating current. These protective materials, it is to be understood, are not limited to use with the double component gas or vapor filling but function in the same manner in lamps having but one gas or vapor such as mercury, helium, or any other.

In the claims the phrase "on the inside of the envelope wall at and near the seal-in point" or a variation thereof has been used to cover the stem commonly used in such devices, or the area adjacent to the electrodes at the seal regardless of construction.

I claim:

1. In an electric vapor discharge device having electrodes sealed into an envelope, a protective coating of a material having a low atomic weight inside of the envelope on the electrode lead-ins at and near the seal-in point.

2. In an electric vapor discharge device having electrodes sealed into an envelope, a protective coating of lithium oxide inside of the envelope on the electrode lead-in at and near the seal-in point.

3. In an electric vapor discharge device having electrodes sealed into an envelope, a protective coating of an alkali oxide having a low atomic weight on the electrode lead-in at and near the seal-in point.

4. In a vapor discharge electric device, comprising a sealed envelope having electrodes sealed thereinto, a covering for parts at and adjacent to the seal-ins of material comprising a metal of low atomic weight.

5. In a vapor discharge electric device, comprising a sealed envelope having electrodes sealed thereinto, a covering for parts at and adjacent to the seal-ins of material comprising a metal of low atomic weight in the oxidized state.

6. In a vapor discharge electric device, comprising a sealed envelope having electrodes sealed thereinto, a covering for parts at and adjacent to the seal-ins of material comprising a metal of low atomic weight and having a high boiling point.

7. In a vapor discharge electric device comprising a sealed envelope having electrodes sealed thereinto, a covering for parts at and adjacent to the seal-ins of material comprising lithium.

8. In a vapor discharge electric device comprising a sealed envelope having electrodes sealed thereinto, a covering for parts at and adjacent to the seal-ins of material comprising lithium in the oxidized state.

9. In a vapor discharge electric device comprising a sealed envelope having electrodes sealed thereinto, a covering for parts at and adjacent to the seal-ins of material comprising a metal of low atomic weight lower than that of metal in the glass at said seal-ins.

10. In a vapor discharge electric device, a

sealed vitreous envelope, electrodes formed on the inner surface of said envelope, and leads sealed through the envelope wall to said electrodes, and a protective coating on said envelope wall between said electrodes.

11. In a vapor discharge electric device, a sealed vitreous envelope, electrodes formed on the inner surface of said envelope, and leads sealed through the envelope wall to said electrodes and a protective coating of an alkali oxide on the interior wall of the envelope between said electrodes.

12. In a vapor discharge electric device, a sealed vitreous envelope, electrodes in said envelope, and electrode leads terminating within a short distance of respective electrodes, portions of the wall of said envelope serving as resistances between the electrodes and their respective leads.

13. In a vapor discharge electric device, a sealed vitreous envelope, electrodes in said envelope, and electrode leads terminating within a short distance of respective electrodes, portions of the wall of said envelope serving as resistances between the electrodes and their respective leads.

Signed at Hoboken, in the county of Hudson and State of New Jersey, this 19th day of February, A. D. 1926.
